UNITED STATES PATENT OFFICE.

MILTON C. HUTTON, OF GEORGETOWN, ASSIGNOR OF ONE-HALF TO J. H. FAUBION AND J. PHIPPS, BOTH OF WILLIAMSON COUNTY, TEXAS.

TRUNK-FASTENING.

SPECIFICATION forming part of Letters Patent No. 440,636, dated November 18, 1890.

Application filed May 13, 1890. Serial No. 351,611. (No model.)

To all whom it may concern:

Be it known that I, MILTON C. HUTTON, a citizen of the United States, residing at Georgetown, in the county of Williamson and State 5 of Texas, have invented certain new and useful Improvements in Trunk-Fasteners; and I do hereby declare the following to be a full, clear, and exact description of the invention, such as will enable others skilled in the art to 10 which it appertains to make and use the same.

My invention relates to an improvement in trunk-fastenings; and my object is to produce a combined catch and brace for the lid which shall be more effective and durable 15 than those heretofore in use, and at the same time cheap and simple in construction.

With this end in view my invention consists in certain peculiarities of construction and combinations of parts, more fully described hereinafter, and set forth in the claim. 20

Referring to the accompanying drawings, Figure 1 represents a front elevation of a trunk provided with my improved fastening devices and shown unlocked with the lid 25 thrown up; Fig. 2, a similar view with the lid closed down and secured, and Fig. 3 a cross-section through line $\alpha\alpha$ of Fig. 2.

The reference-letter A indicates the trunk proper, and B the lid, which is provided with 30 the usual metal strip C, running around its lower edges and fitting over the trunk, the latter being provided with facings D D, one on each side of the lock.

I have shown a pair of my fastening devices—one at each end of the front side of the 35 trunk; but as both are constructed alike a description of but one will be necessary.

A substantially semicircular cleat or block E is secured to the strip C by suitable rivets 40 or brads, and in the inside face of this cleat or that surface adjacent to said strip is formed a semicircular recess or chamber F, provided with a groove or channel G, open at the end nearest the lock, but closed at the opposite 45 end, and bounded by the rib H. The outer surface of the block E projects over the rib to form a semicircular flange I. This cleat or block E forms one section of the catch, and the other portion consists of a circular disk

J, secured to the front face of the trunk by 50 the rivet or pivot K, extending through the facing D and a plate L on the inside. This disk is provided with a ring M, cast with it and projecting from it back of its periphery, and has also a segmental extension N, from 55 the outer rim of which extends a flange O, thus forming between it and the ring M a channel P. Lugs or finger-pieces Q project from the opposite inside faces of the ring M, and a disk is revolved by applying the thumb 60 and forefinger to these lugs. When the lid is shut down, the ring M will fit up to the rib H and beneath the flange I, and when the disk is revolved the flange O will enter the channel or groove G and travel to the end of the 65 same, when it will be wholly contained within said groove, and the rib H will be occupying the channel P, and the lid thus tightly and securely fastened.

As before stated, one of these fastenings is 70 shown on each side of the lock, and the disks are both arranged to be turned away from the latter in locking, so that they can be readily manipulated simultaneously, applying the right hand to one and the left to the other; 75 but it is evident that catches might be located on opposite ends of the trunks, instead of the front. The advantages of this arrangement will be apparent. The lid is not only held securely down at both ends, but the trunk is 80 braced on all sides, thus protecting the hinges and being better fitted to withstand rough usage. Another advantage is that in closing the lid when it has to be forced down the flanges will enter the grooves if the lid does 85 not come squarely down, and upon continuing the revolution of the disk said flanges will travel in the curved grooves and draw down the lid to the proper position. Thus a compact, simple, and ornamental fastening 90 device is produced, having no projections to catch on clothing, &c., and containing no hinges or springs to become broken, and at the same time combining strength, durability, and efficiency.

It is evident that many slight changes which might suggest themselves to a skilled mechanician could be resorted to without departing 95

from the spirit and scope of my invention; hence I do not limit myself to the precise construction herein shown; but,

Having thus described my invention, what 5 I claim as new, and desire to secure by Letters Patent, is—

A trunk-fastening consisting of a stationary block having a segmental groove in its under side, a stop at one end of said groove, an overlapping flange projecting from the outside bounding-rib of said groove, a rotary disk having a segmental extension, a flange projecting from the outer surface of said extension and adapted to enter said segmental 15 groove, a circular flange projecting from the

outside surface of the disk and fitting beneath the overlapping flange of the stationary block, said circular flange forming with the segmental flange a groove arranged to be engaged by the bounding-rib of the groove in the block, and a pair of lugs located within said circular flange and by means of which the disk is turned, substantially as described. 20

In testimony whereof I affix my signature in presence of two witnesses.

MILTON C. HUTTON.
